FLATIRON HANDLE

James L. Terrell, 1020 Broadway St.,
North Chicago, Ill. 60064

Filed Mar. 5, 1969, Ser. No. 16,172

Term of patent 14 years

Int. Cl. D7—06

U.S. Cl. D49—6

FIG.1

FIG.2

FIG.4

FIG.3

FIG. 1 is a side elevation view of a flatiron handle showing my new design, the opposite side being substantially a mirror image thereof except for omission of the square screened area.

FIG. 2 is an elevation view taken from one end thereof;
FIG. 3 is an elevation view taken from the end opposite that shown in FIG. 2;

FIG. 4 is a perspective view thereof.

I claim:

The ornamental design for a flatiron handle, as shown and described.
